(57) **CLAIM**

The ornamental design for a detector, as shown and described.

DESCRIPTION

FIG. 1 is a perspective view of a detector showing our design according to a first embodiment.

FIG. 2 is a right-side view of the detector of FIG. 1.

FIG. 3 is a left-side view of the detector of FIG. 1.

FIG. 4 is a front view of the detector of FIG. 1.

FIG. 5 is a rear view of the detector of FIG. 1.

FIG. 6 is a top view of the detector of FIG. 1; and,

FIG. 7 is a bottom view of the detector of FIG. 1.

The portions of the detector shown in short broken lines are for illustrative purposes and form no part of the claimed design. The surface features illustrated in the drawings are coplanar/flat.
